UNITED STATES PATENT OFFICE.

HANNS KLEMM, OF SINDELFLINGEN, GERMANY, ASSIGNOR TO DAIMLER-MOTOREN-
GESELLSCHAFT, A CORPORATION OF THE REPUBLIC OF GERMANY.

LATCHING DEVICE FOR WINDOW WINGS, DOORS, AND THE LIKE.

Application filed September 1, 1923. Serial No. 660,472.

To all whom it may concern:

Be it known that I, HANNS KLEMM, a citizen of the State of Wurttemberg, Germany, residing at Sindelfingen, Wurttemberg, Germany, 38 Bahnhofstrasse, have invented certain new and useful Improvements in a Latching Device for Window Wings, Doors, and the like, of which the following is a specification.

10 This invention relates to a device for latching window-wings, doors, and the like, which latching device is constructed in such a manner that it is actuated automatically, when the window-wing or door etc. is either closed or opened, and thereby adjusted to and from its operative position and vice versa.

The gist of the invention resides in providing a latching means proper consisting 20 of two or more elements which are staggered in such relation to each other that, when the device is for instance in the latching position, one of said elements will be located between the swinging vertical edge of the door 25 or window-wing and the other element will be located outside of the door or wing in such a way as to form an abutment therefor whereby the door or window is latched in its closed position. The two elements mentioned are movable horizontally, and are generally speaking moved through an angle of about ninety degrees. The elements referred to may be connected with each other in such a manner that the movement of one 30 of them is transmitted to the other, either in the same direction or in a reverse direction, according to the arrangement and combination of the connecting members. The horizontally movable elements are also vertically movable, and if the two elements move in the same direction, the lengths of their respective paths of movement may be equal or unequal.

One form of construction of the invention 45 may consist, for instance, of two or more co-axial vertical shafts, or sections of a shaft, carrying lateral arms or the like which extend through oblique slots provided in relatively stationary guide members. The arms or the like are staggered, generally at approximately 90° to each other, and the slots are inclined in the same directions with respect to each other. Assuming that a window-wing is connected with such vertical shaft or shaft section, and the wing is swung

on its pivots, then the shaft will be correspondingly rotated in the same direction, but it will also be lifted to an extent corresponding to the inclination of the slot engaged by the arm or the like pertaining to that shaft or shaft section. Simultaneously therewith, the other shafts or shaft sections will be rotated, as well as lifted, by their arms and the cooperating slots, because of the fact that the movement of the first shaft 65 or shaft section is transmitted to the other shaft or shaft section, whereby the wing, or the door, is latched or released, according to the direction of the movements.

If desired, those parts which hold fast the 70 door or the window-wing may cooperate with a guide slot, the inclination of which is slightly less than the inclination of the guide slot with which those parts which are moved by the door or the wing cooperate; 75 the path of the parts which abut against the door or the wing in such case is correspondingly longer than that of the other movable members forming part of the locking device. In this way a very accurate and firm fitting 80 of the door or window in its frame is attained, together with a certain yieldingness, especially if the element which holds the door or window-wing is provided with a resilient or an elastic lining or the like. On 85 the whole the latching device is very simple, and reliable in action.

My invention is illustrated diagrammatically by way of example in the accompanying drawing, in which Fig. 1 is a perspective illustration of a window-wing forming part of the body of a motor-car, the window being closed; Fig. 2 is a similar illustration, showing the same window-wing in an open position; Fig. 3 is a detail perspective view of the latching device provided on the stationary part of the body at the right-hand of the window-wing and Fig. 4 is a plan view of this device.

The window-wing *a* is attached to the 100 body-part *b* by means of the hinges *c*, and the latching device *e* is attached to the body part *d*. In the example shown, this device consists of two shaft sections *f*, *f'*, arranged co-axially and each provided with a horizontal arm or pin *m* or the like extending radially therefrom and carrying a preferably rectangular plate *g*, *g'*; the two plates are arranged at right angles with respect to each other as shown in Fig. 4. The arms 110

or pins m extend from the shaft sections f , f' through inclined or oblique slots h , h' , provided in cylindrical members i , i' , which surrounds the shaft sections. One of the latter, f' in the example shown, is connected with a spiral spring k which tends to turn the shaft in a certain direction, either so as to adjust the latching device to a closed position or so as to shift it to an open position. The inclination of the slot h' may be less than that of the slot h , so that when the parts are brought to the position shown in Fig. 1, the plate g' will engage the wing or door under an increased pressure. That is to say, if the slots h and h' are correspondingly inclined, the swinging movements of the plates g and g' will be of equal extent and the wing or door a will be engaged by the plate g' with perhaps only a slight pressure. If, however, the inclination of the slot h' is less than that of the slot h , then the adjustment of the plate g' is such that it is pressed against the door or wing to greater extent. The object of this arrangement is to obtain a secure closure of the wing, or of the door respectively, if the wing or the door is capable of yielding to a certain extent with respect to the car body, etc. In such a case, the plates may be provided with a resilient cushion, as for instance a piece of rubber 1, Fig. 3, to permit the aforesaid adjustment of the plate g' .

The position of the plates g , g' , in Fig. 3 corresponds to the position of the parts in Fig. 2 in which the window wing is open. The plate g projects in the direction of the wall, of the car body, and the other plate projects outwardly approximately at right angles thereto. The position of the plates is changed when the wing is closed, the plate g being then turned inwardly (Fig. 1) and the plate g' being turned toward and over the door or wing so as to keep it closed. In other words, as the wing, door, or the like is moved from the closed position shown in Fig. 1, toward the open position of Fig. 2, the pressure exerted thereby upon the plate g' will swing the latter and the plate g to the position shown in Fig. 2; similarly as the wing, door or the like is closed the pressure exerted thereby upon the plate g will adjust the latter and the plate g' back to the position illustrated in Fig. 1. In the latter position, the plate g is located between an edge of the wing, door or the like and a contiguous edge of the casing, body, or equivalent element and serves to press the plate g' against the wing, door or the like, over a face of which said plate g' extends, to fix said wing, door, or the like in its closed position. Owing to the fact that the slots h , h' are inclined, the shaft f , f' , is correspondingly lifted and the spring k correspondingly compressed as the door or wing is moved toward its closed position.

When the door is opened, the plates g , g' , are moved back into the positions they occupy in Fig. 3 in which they are also retained by the spring k which is always under a certain tension.

70

I claim:

1. A latching device for hinged members such as doors, window-wings, and the like, comprising, in combination, a spindle mounted upon the frame of the hinged member, and a pair of members extending radially outward from said spindle in directions at an angle to each other one of said members extending over a face of said hinged member in the closed position of the latter and the other member of said pair coincidentally extending between an edge of said hinged member and a contiguous edge of its casing to press the first named member against said face of the hinged member and thereby fix the latter in said closed position, said pair of members being actuated by hinged member.

2. A latching device for hinged members such as doors, window-wings, and the like, comprising, in combination, two latching plates arranged at some distance from, and at right angles relatively to each other, coaxial shaft sections, arms extending therefrom at right angles and carrying said plates, and tubular members enclosing said shaft sections and each having a slot through which the cooperating arm extends outwardly, substantially as described.

3. A latching device for hinged members such as doors, window-wings, and the like, comprising, in combination, two latching plates arranged at some distance from, and at right angles relatively to each other, coaxially arranged shaft sections, means for transmitting motion from one to the other, arms extending from said shaft sections at right angles therefrom and carrying said plates and tubular members enclosing said shaft sections and each having a slot through which the cooperating arm extends outwardly, substantially as described.

4. A latching device for hinged members such as doors, window-wings, and the like, comprising, in combination, two latching plates arranged at some distance from, and at right angles relatively to each other, coaxial shaft sections, arms extending therefrom at right angles and carrying said plates, tubular members enclosing said shaft sections and each having an inclined slot through which the cooperating arm extends outwardly, substantially as described.

5. A latching device for hinged members such as doors, window-wings and the like, comprising, in combination, two latching plates arranged at some distance from, and at right angles relatively to each other, coaxial shaft sections, arms extending therefrom at right angles and carrying said

125

135

plates, and tubular members enclosing said shaft sections and each having an inclined slot through which the cooperating arm extends outwardly, the inclination of the slots being different, substantially as described.

6. A latching device for hinged members such as doors, window-wings, and the like, comprising, in combination, two latching plates arranged at some distance from, and at right angles relatively to each other, co-

axial shaft sections, arms extending therefrom at right angles and carrying said plates, tubular members enclosing said shaft sections and each having a slot through which the cooperating arm extends outwardly, and a spring so arranged as to ensure contact between said shaft sections, substantially as described. 15

In testimony whereof I affix my signature.

HANNS KLEMM.
